(57) **CLAIM**

The ornamental design for a lift-up cleat, as shown and described.

DESCRIPTION

FIG. 1 is a top perspective view of a lift-up cleat, showing my new design;

FIG. 2 is an end elevational view, wherein the opposite end elevational view is substantially identical;

FIG. 3 is a front elevational view, wherein the rear elevational view is substantially identical; and,

FIG. 4 is a top plan view thereof.
